His Attorney.

UNITED STATES PATENT OFFICE

CROMWELL A. B. HALVORSON, OF LYNN, MASSACHUSETTS, ASSIGNOR TO GENERAL ELECTRIC COMPANY, A CORPORATION OF NEW YORK

FIXTURE FOR ELECTRIC LAMPS

Application filed November 17, 1928. Serial No. 320,141.

My invention relates to fixtures for electric lamps of the type especially adapted for use in connection with street or highway lighting. One of the objects of the invention is to provide in the fixture a body or holder of ceramic material, such as porcelain, within which adjustable socket terminals of special construction are housed, and through the walls of which holder connections are made from the terminals to outside line terminals. Another object of the invention is to provide the holder with an improved form of metal cap to which the holder is secured, the cap being flared to form a skirt to protect the upper portion of the holder from the weather. Another object of the invention is to provide improved means for securing a reflector to the lower portion of the holder. This last feature is the subject matter of my divisional application, Serial No. 394,099, filed September 20, 1929.

However, the invention in all its details will be more fully understood from the following specification and claims, reference being had to the accompanying drawings in which Fig. 1 shows a section in elevation through the fixture, and Fig. 2 shows an enlarged section of the holder with a lamp socket in position therein. In Figure 2 the adjusting mechanism is shown in an inverted position from that shown in Fig. 1.

Referring to the drawings, the fixture comprises a container, holder or casing element 2, which is preferably made of porcelain. This container is provided with a skirt 3 near the mid portion. Just below this skirt there are provided binding posts 4 and 5, one on either side of the container. These binding posts are in threaded engagement with metal terminals 6 and 7 within the holder. The terminal 6 comprises an arm *b* which extends along the inner surface of casing 2 and an angularly extending arm *d*, and the terminal 7 comprises an arm *a* which extends along the inner surface of casing 2 and an angularly extending arm *c*. Clamped between the binding posts 4 and 5 and the holder I provide tie lugs 8 and 9 respectively. Each tie lug is provided with a double stirrup arrangement each having an outer loop such as the loops 10 and 11, and an inner loop such as the loops 12 and 13, both of which loops close in upon the base portion of the tie lug which is inserted between the binding post and the porcelain. With this arrangement it is possible to bring in the line leads one to the terminal 4 and the other to the terminal 5, threading them first through the stirrup portions of their corresponding terminals.

The holder is provided with a metal cap 14 which is secured in any suitable manner to the holder 2, such as, for example, by means of heavy screws which project through the cap along the region just above the skirt 15 and engage holes in the holder 2. The cap 14 may be secured in any suitable manner to a support, but preferably the cap is provided with threads 16 which may be screwed to an iron pipe, for example, as a support.

The reflector 17 is provided with a collar section 17' which fits into the lower cavity of the holder. On the outside of the holder I provide a metal band 18 which is threaded and through which, and through corresponding holes in the porcelain the screws project to engage and hold the collar 17' of the reflector.

Within the holder the terminals 6 and 7 are provided each respectively with spring contacts 19 and 20, each of which is electrically secured to the corresponding terminal arms *d* and *c*. The lamp socket 21 is also provided with spring contacts 22 and 23. The socket 21 may be inserted in position as indicated in Fig. 1 by forcing the spring contacts 22 and 23 in between the spring contacts 19 and 20. When this is done the spring contacts 19 and 20 are separated and the lamp 24 is thus connected in series with the terminals 4 and 5. An element of insulating material 25 is interposed between the spring contacts 22 and 23. This element serves as a series cutout which, if the lamp 24 burns out, breaks down and establishes a series circuit through the fixture. The arms *a* and *b* are provided each with a series of threaded holes 26, 27, 28,

and 29 in addition to the threaded holes engaged by the binding posts 4 and 5 so that the spring contacts 19 and 20 may be adjusted along the axis of the fixture above or 5 below the axis of support through the binding posts 4 and 5 with the arms *a* and *b* pointing up or down. This arrangement enables the socket 21 to be adjusted within the holder along the axis of the fixture to 10 accommodate lamps of different lengths.

In Fig. 2 the terminals 6 and 7 are shown inverted so that the socket 21 is thus placed in the maximum raised position.

It will be seen, therefore, that I provide 15 an improved lighting unit fixture in which the porcelain element is provided with a skirt for enabling water, for example, in the case of rain, to drip from the skirt rather than run down the sides. In this way a 20 higher condition of insulation is maintained between the terminals 4 and 5 and the cap 14. In a similar way the skirt 15 on the cap 14 increases the insulation between the same terminals and the cap 14. The fixture 25 has in addition this advantage that by providing the metal band 18 for the screws which support the reflector 17, the porcelain body 2 is relieved of any lateral strain, the strain being taken altogether by the band 30 18. The only strain that is placed upon the holder is the strain due to the weight of the reflector.

It will be understood that while I have elected to describe my invention in connection 35 with the specific form of apparatus shown, I do not wish to be so limited inasmuch as in view of the disclosure other variations and modifications are contemplated which do not depart from the spirit 40 of the invention and which fall within the scope of the claims contained herein.

What I claim as new and desire to secure by Letters Patent of the United States, is:

1. In a lighting fixture, the combination 45 of a casing, terminals in the casing each comprising an arm which extends along the inner wall of the casing and an arm which projects at an angle thereto toward the center of the casing, said first-named arms 50 being adjustable along the wall of the casing, spring contacts carried by the ends of said angularly projecting arms, and binding posts which extend through the casing and engage said first-named arms to hold the 55 terminals in adjusted position and to make electrical contact therewith.

2. In a lighting fixture, the combination of 60 a casing, terminals in the casing each comprising an arm which extends along the inner wall of the casing and an arm which projects at an angle thereto toward the center of the casing, said first-named arms being provided with a series of spaced openings, spring contacts carried by the ends of said angularly 65 projecting arms; and binding posts which

extend through the casing and are adapted to engage selected openings in said first-named arms to hold the terminals in adjusted positions.

3. In a lighting fixture, the combination 70 of a casing, terminals in the casing each comprising an arm which extends along the inner wall of the casing and an arm which projects at an angle thereto toward the center of the casing, said first-named arms being provided with a series of spaced openings, spring contacts carried by the ends of said angularly projecting arms, and binding posts which extend through the casing and are adapted to engage selected openings in 75 said first-named arms to hold the terminals in adjusted positions, said spring contacts being detachably connected to said angularly projecting arms whereby they may be located on either side of the same.

4: In a lighting fixture, the combination of 80 a casing, terminals in the casing each comprising an arm which extends along the inner wall of the casing and an arm which projects at an angle thereto toward the center of the casing, said first-named arms being adjustable along the wall of the casing, 85 spring contacts carried by the ends of said angularly projecting arms, binding posts which extend through the casing and engage said first-named arms to hold the terminals in adjusted position and to make electrical contact therewith, and means supported by 90 said binding posts on the outside of the casing to which a lead wire may be fastened for relieving strain on the binding posts.

5. In a lighting fixture, the combination of 95 a casing, terminals in the casing each comprising an arm which extends along the inner wall of the casing and an arm which projects at an angle thereto toward the center of the casing, said first-named arms being adjustable along the wall of the casing, 100 spring contacts carried by the ends of said angularly projecting arms, binding posts which extend through the casing and engage said first-named arms to hold the terminals in adjusted position and to make electrical contact therewith, and strain relieving loops 105 supported by said binding posts.

In witness whereof, I have hereunto set my hand this fifteenth day of November, 1928.

CROMWELL A. B. HALVORSON.
